METHOD OF GRINDING FLAT COIL SPRING BANDS AND A WORK HOLDER THEREFOR

Hans J. Duester, Chicago, Ill., assignor to himself and John Major, Chicago, Ill.

Application August 30, 1948, Serial No. 46,730

4 Claims. (Cl. 51—217)

1

My invention relates to a new and improved method of grinding flat coil spring bands and a work holder therefor.

My invention relates more particularly to the method of grinding flat coil spring bands of the type used for ornamental purposes such as extensible bands for watch bracelets or similar articles, choker necklaces or bracelets.

Extensible wrist watch bands and bracelets of this type have come into popular use in the last few years, the same having advantages over other types of bracelets, particularly due to their ease of attachment or removal and partially due to decorative features which can be embodied therein.

The method which I have devised and the work holder which I have provided therefor are adapted to be used in providing decorative grooves of various types in bands of this description, the grooves serving to enhance the appearance of the extensible spring bands.

The principal object of the present invention is to provide a new and improved method of grinding decorative grooves in coiled spring bands of the type described.

A further object of the invention is to provide a new and improved work holder or fixture for holding flat bands of this type during the grinding operation thereon.

A further object of the invention is to provide an improved work holder or fixture of the type described which is capable of holding one or more coils of the extensible band in a lowered position, depressed below the surface of others so that alternate coils of the band may be ground, thereby creating varied decorative surface configurations in the complete band.

A further object of the invention is to provide a work holder or fixture of the type described by which such decorative grinding can be rapidly and efficiently done in a minimum of time and with such accuracy that volume production of decorative bands can be accomplished.

Other objects and advantages will be more apparent from the following description wherein reference is had to the accompanying drawings, upon which

Fig. 1 is an enlarged fragmentary view of a portion of a flat coiled spring band showing a plurality of parallel grooves in alternate coils of the band;

Fig. 2 is a cross-sectional view taken on the line 2—2 of Fig. 1 showing the grinding of the grooves in one of the coils;

Fig. 3 is a similar cross-sectional view taken

2

on the line 3—3 of Fig. 1 showing the grinding of the grooves in alternate coils;

Fig. 4 is an enlarged fragmentary plan view similar to Fig. 1, showing a modified decorative groove in the face of the spring band, alternate coils again being similar;

Fig. 5 is a cross-sectional view taken on the line 5—5 of Fig. 4 showing the manner in which the grooves therein are ground;

10 Fig. 6 is a similar sectional view taken on the line 6—6 of Fig. 4 showing the manner in which the alternative grooves are ground;

Fig. 7 is a plan view of the fixture or work holder in which the extensible coiled spring band 15 is placed to be held for grinding;

Fig. 7—A is a perspective view of the lining arbor which I employ;

Fig. 8 is a side elevational view of the work holder or fixture;

20 Fig. 9 is a cross-sectional view thereof taken on the line 9—9 of Fig. 8;

Fig. 10 is an enlarged fragmentary sectional view showing a portion of the mechanism shown in Fig. 9;

25 Fig. 11 is a fragmentary plan view thereof; and Fig. 12 is a similar fragmentary plan view showing a modified construction wherein several parallel coils are ground at the same time, others being held against grinding.

30 The method which I have provided for grinding decorative grooves in flat coiled springs is best shown in Figs. 1 to 6 inclusive, wherein in Fig. 1 I have shown a section of flat coiled spring band 10 consisting of the individual coils or convolutions 11, 12, 13, 14, etc. It will be noticed that each of the top surfaces of the coils 11, 13, etc., have surface grooves 15, and each of the top surfaces of the coils 12, 14, etc., have surface grooves 16, the grooves being staggered so that

35 on a full size band, which is ordinarily $\frac{1}{8}$ of an inch wide, the placement of the grooves as shown in the enlarged grooves—Figs. 1 to 3 inclusive, give the appearance of a chain design.

40 The grooves are made in the top surfaces of the separate coils or convolutions by grinding wheels G mounted on a spindle and driven in a manner that is well-known in the art.

45 In the method of grinding which I am about 50 to describe, all of the grooves 15 are first placed in the alternate coils 11, 13, etc., the convolutions 12, 14, etc., being held down during this grinding operation; and in a different setting which will presently be explained, the convolutions 11, 13, etc., are held down and the grooves

16 are ground in the top surfaces of the convolutions 12, 14, etc.

In Figs. 4 to 6 I have shown how the same method of grinding may be utilized where variations in the design or pattern are sought. For example, in the spring band 20 shown in Fig. 4 and consisting of the convolutions 21, 22, 23, 24, etc., each of the convolutions 21, 23, etc. has a comparatively wide flat groove 25 ground therein by the grinding wheel G, the alternate convolutions 22, 24, etc. being held down during this grinding operation and the convolutions 22, 24, etc. having the elongated groove 27 ground therein by the grinding wheel in a different setting when the alternate convolutions 21, 23, etc. are being held down.

From the above description of two different types of designs which may be ground into the top surfaces of the individual coils or convolutions, it can be seen that a wide variety of different patterns can be conceived and ground by the process which I am about to describe.

In carrying out the above process, I provide a work holder or fixture which may include a base 30 adapted to be mounted upon a magnetic support 32. The base 32 may be generally rectangular, as shown in Figs. 7 to 9 inclusive, and have a pair of parallel guide blocks 34 and 36 defining a rectangular space therebetween throughout their length. I mount a pair of suspension and eliminating jaws 38 and 40 on the top of the guide blocks 34 and 36 respectively, the same being fixedly held in position by suitable screw members 42. I provide a wedge 44 positioned for up and down movement in the space between the guide blocks, the wedge being generally rectangular in shape, but having a top surface tapered from the center outwardly to both edges at approximately 5°. Means for raising or lowering the wedge block may comprise the lifter member 48 which is also guided between the blocks 34 and 36 and has the tapered surface 50 which bears against the lowered tapered surface 52 of the wedge block.

Any lateral movement of the wedge block between the guide blocks 34 and 36 is prevented in the back end of the fixture by the end post member 54 which extends across the face of the ends of the guide blocks 34 and 36 and at the front end of the fixture by a fastener block 56 which is fastened to the front end of block 34 and has a finger portion 58 extending across the end of the wedge block 44 at its front end.

Means for moving the wedge lifter 48 back and forth may comprise the pivoted lever 60 having a head 62 mounted for rotation on a pin 64 fastened to the base 30. The head 62 may have an elongated slot 66 adapted to receive an upright pin 68 on the end of the wedge lifter 48.

To fixedly secure an extensible chain band B in position in the work holder so that alternate convolutions or coils may be raised for grinding and others depressed, I place the band on a lining arbor 70 shown in perspective in Fig. 7-A. The liner 70 is a comparatively long parallel-edged strap having a flat upper surface 72 and a lower surface 74, which surface tapers upwardly from the center to both edges at approximately 2½°. The end of the lining arbor has a semi-circular groove 76 which, when the arbor with a band mounted thereon is extended into the work holder, engages the stop pin 78 mounted upon the end post member 54, the band itself abutting against the forward wall of the post.

When a band has been inserted into the work

holder on the arbor 70 in the position shown in Figs. 7 and 9 and the operating lever 60 has been swung to the right (Fig. 7), the wedge lifter 48 will be moved forward and the separate convolutions of the band will take the position shown in Fig. 9 and enlarged in Fig. 10. Referring to Fig. 10, it will be noticed that the depressed convolutions 12 are wedged between the top surface of the lining arbor 70 and the suspension and eliminating jaws 38 and 40.

The jaws, as best shown in Fig. 11, have alternate slots 82 and teeth 84, the unlowered coils or convolutions reposing in the slots 82 and the lowered convolutions 12, 14, etc. being jammed by the teeth 84 downwardly against the top of the lining arbor 70. In this condition the bottom portions of the coils or convolutions rest at an angle so that alternate convolutions rest against the tapered top of the wedge block 44 and the tapered lower side of the lining arbor 70. Thus it can be seen that alternate convolutions of the coiled spring band are held depressed below the depth at which grinding of the decorative grooves is desired, the grinding wheels G mounted upon a suitable driven shaft which may now be moved back and forth across the top of the entire band, thus making the desired grooves in the top surfaces of alternate convolutions.

After the operation has been completed, the operating lever 60 may be moved clockwise to release the wedge block, the lining arbor may be withdrawn with the band and the next band inserted for the same operation.

From the above and foregoing description it will be apparent to those skilled in the art that I have provided a comparatively simple yet efficient and accurate method of grinding decorative grooves of the type described as well as a highly efficient and accurate mechanism for carrying out the method. By the use of this method and process, bands of this type can be accurately and quickly ground without injuring the tensile strength of the material of which the bands are constructed or disfiguring or in any way interfering with the function of the same as they would function if the grinding operation had not taken place.

From the foregoing description it will be obvious that by a variance in the construction of the suspension and eliminating jaws different designs may be produced with the same method and by the use of the same mechanism. For example, the teeth and spaces may be so defined that two or three coils together will be depressed, permitting alternate groups of more than one coil to be grooved with the same design, and then the grooved convolutions may be depressed to permit a different design in the unground convolutions.

While I have illustrated and described a specific embodiment of the invention and one other use for the same, it will be apparent to those skilled in the art that changes and modifications may be made in the exact details shown and I do not wish to be limited in any particular; rather what I desire to secure and protect by Letters Patent of the United States is:

1. The method of decorating flat extensible spring coils which comprises inserting a rigid filler strip into the coil partially to fill and rigidify the coil, applying upward pressure to the assembled coil and filler strip from below the assembly while simultaneously firmly resisting such pressure from above every other convolution of the coil along the edges of the coil so that only the intermediate alternate convolutions are

raised above said first mentioned convolutions by the upward pressure and then cutting patterns in the raised exposed flat faces of the intermediate alternate convolutions, and then removing the filler strip.

2. The method of decorating flat extensible spring coils which comprises inserting a rigid filler strip into the coil partially to fill and rigidify the coil, applying upward pressure to the assembled coil and filler strip from below the assembly while simultaneously firmly resisting such pressure from above one or more spaced convolutions of the coil along the edges of the coil so that only the intermediate alternate convolutions between the aforementioned one or more convolutions are raised above said first mentioned spaced convolutions by the upward pressure and then cutting patterns in the raised exposed flat faces of the intermediate alternate convolutions, and then removing the filler strip.

3. A work holder for flat coiled springs comprising a base, spaced parallel walled guide blocks mounted on said base, a pair of similarly shaped horizontally disposed jaw members fixedly mounted on said guide blocks, each of said jaw members having a row of spaced diagonally directed teeth on one side wall, the jaw members so arranged on said guide blocks that the rows of teeth are opposed and directed at an angle toward each other and a tapered channel is formed between said jaw members, a wedge having parallel side walls mounted between said guide blocks, a wedge lifter slidably mounted below said wedge, said wedge lifter adapted when moved in a lateral direction to raise said wedge toward said rows of spaced teeth, a flat coiled spring positioned on said wedge, an elongated arbor telescopically mounted therein, said coiled spring adapted to be placed on said wedge to present alternate coils of said band to the opposed rows of teeth to hold them against movement while adjacent coils are raised for grinding by movement of said wedge lifter, said wedge having a medial peak in its upper surface and said arbor being generally rectangular in cross-section and having a medial peak in its bottom surface whereby the bottom legs of alternate coils of the band are rigidly clamped between the tapered surfaces of the top of said wedge and the bottom of said arbor to present alternate coils of said spring raised above the rest of the coils.

4. A work holder for flat coiled springs comprising a base, spaced parallel walled guide blocks mounted on said base, a pair of similarly shaped horizontally disposed jaw members fixedly mounted on said guide blocks, each of said jaw mem-

bers having a row of spaced diagonally directed teeth on one side wall, the jaw members so arranged on said guide blocks that the rows of teeth are opposed and directed at an angle toward each other and a tapered channel is formed between said jaw members, a wedge having parallel side walls mounted between said guide blocks, a wedge lifter slidably mounted below said wedge, said wedge lifter adapted when moved in a lateral direction to raise said wedge toward said rows of spaced teeth, a flat coiled spring positioned on said wedge, an elongated arbor telescopically mounted therein, said coiled spring adapted to be placed on said wedge to present alternate coils of said band to the opposed rows of teeth to hold them against movement while adjacent coils are raised for grinding by movement of said wedge lifter, said wedge having a medial peak in its upper surface and said arbor being generally rectangular in cross-section and having a medial peak in its bottom surface whereby the bottom legs of alternate coils of the band are rigidly clamped between the tapered surfaces of the top of said wedge and the bottom of said arbor to present alternate coils of said spring raised above the rest of the coils.

HANS J. DUESTER.
